UNITED STATES PATENT OFFICE.

NICOMEDES F. REYNAL O'CONNOR, OF BUENOS AIRES, ARGENTINA.

MEDICINE-CONTAINER.

1,333,935.

Specification of Letters Patent. Patented Mar. 16, 1920.

Application filed July 18, 1919. Serial No. 311,779.

To all whom it may concern:

Be it known that I, NICOMEDES FRANCISCO REYNAL O'CONNOR, a citizen of Argentina, and residing at Buenos Aires, Argentina, 5 have invented certain new and useful Improvements in Medicine-Containers, of which the following is a specification.

The present invention relates to medicine containers or capsules.

10 The principal objects of the invention are to provide an article of this type which when used may be automatically filled with a predetermined quantity of fluid, and to provide a capsule which may be automatically filled without immersing the fingers or an instrument in the fluid. Other objects and features of novelty will be apparent from the description taken in connection with the drawings in which:

20 Fig. 1 is a side elevation of a container constructed in accordance with the present invention showing the container with one end immersed in a fluid in the proper position for filling;

25 Fig. 2 is a sectional elevation of the container; and

Fig. 3 is an elevation of the container after it has been filled with a fluid, certain portions being shown in section.

30 Referring to the drawings the container of the present invention comprises a sealed hollow shell 10, preferably of glass, from which the air has been exhausted. The exhausting of the air and the sealing of the 35 capsule may be accomplished in any of the well known ways. The container 10 is provided at one end with a part which is adapted to be immersed in a fluid and then broken to provide a pin-hole opening

40 through which the shell is filled with the fluid. As shown, the shell 10 is tubular and has the extension 11 of gradually reduced diameter. At 12 this extension is bent back on itself thus forming a bight and a free 45 arm 13. As clearly shown in Fig. 2, the extension 11 is provided with a passageway which is in combination with the interior of the shell 10 and extends at least to the bight 12. This passageway is of gradually

50 reduced diameter so that at the bight 12 a capillary tube is provided. The extension is weakened at the bight so that when the arm 13 is moved laterally said arm will break off at the bight, thus providing an 55 inlet of very small diameter at the bight through which fluid may enter into the shell

to fill the same. As this inlet is of such small diameter the fluid will not leak out of the container.

The end of the shell 10 opposite the extension 11 is provided with a short extension 14 formed with an interior passageway in communication with the interior of the shell 10, the upper end of which is sealed as at 15. When it is desired to withdraw the contents of the container the seal 15 is broken and a hypodermic syringe is connected to one of the extensions 11 or 14 to withdraw the fluid, air entering through the other extension.

In using the container of this invention the bight 12 is immersed in the medicine with which it is desired to fill the container, it being understood that the containers are made in different sizes to hold predetermined quantities of medicine. Then the arm 13 is broken off at the bight 12 by grasping the tip of the arm and moving it away from the container. The break will occur at the bight as this is the weakest part of the extension. Thereupon the fluid will rush through the small inlet, thus substantially filling the container 10. As the container is made to hold a predetermined quantity of medicine, this quantity will be automatically measured out in the filling of the container. As the inlet opening is so very small, none of the medicine will leak out of the container so that the container may be kept indefinitely or until the medicine is required for use. In order to withdraw the medicine from the capsule the seal 15 is broken and then if the medicine is to be used in a hypodermic syringe said syringe is connected to one of the extensions 11 or 14 and the medicine withdrawn from the container, air entering through the opposite extension.

From the foregoing it is apparent that the container of this invention provides an exceedingly simple means for measuring out and storing a predetermined quantity of medicine. Furthermore, the container may be filled with medicine without the use of an instrument or immersing the fingers in the medicine.

Although a specific form of the invention has been described in detail, it is to be understood that it is not thus limited but includes modifications and changes which come within the scope of the appended claims.

Having thus described the invention what

is claimed as new and desired to be secured by Letters Patent is:

1. An article of manufacture of the character described comprising a container from 5 which the air has been exhausted and a tubular U-shaped part having one of its legs connected to the container and formed with a passage communicating with the interior of the container and extending at least to 10 the foot of the said leg, the curved section of said part being weakened whereby the free leg may be broken off to open said passage, which is reduced to capillary size at the weakened portion.
- 15 2. An article of manufacture of the character described comprising a tubular glass container from which the air has been ex-

hausted having an extension of reduced diameter bent back on itself forming a bight, said extension formed with a passage 20 communicating with the interior of the container, and being weakened at the bight, said passage being reduced to capillary size at the bight.

3. An article of manufacture of the character described comprising a tubular glass container from which the air has been exhausted having reduced hollow extensions at both ends, one extension having a tip 25 adapted to be broken off and the other extension being bent back on itself forming a bight and being weakened at the bight.

In testimony whereof I affix my signature.
NICOMEDES F. REYNAL O'CONNOR.
